UNITED STATES PATENT OFFICE.

OLAF RETTEDAL AND NIELS JOSEPH NELSON, OF MINNEAPOLIS, MINNESOTA.

ELLIPSOGRAPH.

Application filed October 11, 1924. Serial No. 743,104.

This invention has for its object to provide an extremely simple but highly efficient tool for drawing ellipses of various sizes.

It is a further object to provide a device for drawing an ellipse which will permit of the speedy regulation of the device to draw an ellipse of desired major and minor axes.

It is a more specific object of the invention to provide an ellipsograph consisting of a T-shaped member having a straight edge along its top side, and a guideway in the stem of the T at right angles thereto, and a scribing arm having members adapted to engage said guideway and said straight edge to generate an ellipse from a tracing point on said arm when said arm is properly manipulated.

These and other objects of the invention will be apparent from the following description made in connection with the accompanying drawings wherein like characters refer to similar parts throughout the several views, and in which,

Fig. 1 is a plan view of the device with the moved position of some of the parts shown in dotted lines;

Fig. 2 is a side elevation of the invention with the scribing arm in alignment with the minor axis of the ellipse to be drawn, some parts being broken away;

Fig. 3 is a plan view of the scribing arm detached; and

Fig. 4 is a vertical section taken on the line 4—4 of Fig. 2.

Referring to the drawings, the invention comprises two parts, one, a T-shaped member and the other a scribing arm or tool adapted to be manipulated and guided by said T-shaped member. The T-shaped member has a straight edge 5 along its top side, one side of which is graduated from a central point therealong. The stem of the T-shaped member 6 is provided with a guideway 7, preferably in the form of a groove, extending at right angles to the straight edge 5. The scribing arm preferably comprises two telescoping members 8 and 9, the member 8 having a split end 10 with a socket therein adapted to resiliently hold a tracing point 11. A set screw 12 permits the member 8 to be rigidly secured to member 9 in a desired telescoped position. A pair of guide pins 13 and 14 are slidably

mounted on the member 9 of the scribing arm which are equipped with set screws 15 and 16 adapted to rigidly secure said pins to the member 9 at desired positions thereon. The members 13 and 14 are adapted to engage, respectively, the straight edge 5 and the guideway 7 of the T-shaped member. 60

Operation.

The movable parts on the scribing arm are first set to produce the ellipse of the major and minor axes desired. This is done by 65 setting the slideable member 13 at a distance from the scribing point 11 equal to the minor semi-axis and setting the member 14 at a distance from the scribing point 11 equal to the major semi-axis. When the set screws 15 and 16 are tightened the tool is ready for use. The end of the pin 14 is inserted in the groove or guideway 7 while the end of pin 13 is pressed against and moved along the straight edge of the T-shaped member 70 from side to side. The movement of the scribing arm will cause the scribing point to draw a complete half of an ellipse, as shown in Fig. 1. The T-shaped member may then be inverted with the straight edge 80 along the major axis of the ellipse to be drawn, as before, and the operation repeated to draw the other half of the ellipse. With the telescoping member 8 a wide range is permitted in the size and proportions of 85 ellipses capable of being drawn with the device.

The instrument works with great precision, is easily handled and set and may be used for inking if the curve drawn is not 90 very flat. The scribing point 11 will draw a substantially perfect ellipse if the pins are properly confined and moved in the guideway and along the straight edge respectively. 95

Obviously the device comprises extremely few parts and may be manufactured at little cost.

It will be understood that various changes in the form, details and arrangements of 100 the parts may be made without departing from the scope of the invention.

What is claimed is:

An ellipsograph comprising a substantially flat member having an elongated rectilinear guide and having a groove extending 105

from the mid-point of said guide and at right angles thereto, a hollow scribing arm, a pin slidable on said arm and adapted to engage said rectilinear guide, means for rigidly securing said pin with said scribing arm, a second pin mounted on said scribing arm adapted to engage said groove and a

scriber carrying member adapted to telescope within said scribing arm.

In testimony whereof we affix our signatures.

OLAF RETTEDAL.
NELS JOSEPH NELSON.
